UNITED STATES PATENT OFFICE.

WILLIAM H. PALMER AND JAMES F. PALMER, OF PITTSBURGH, PENNSYLVANIA; SAID
JAMES F. PALMER ASSIGNOR TO SAID WILLIAM H. PALMER.

INTERNAL-COMBUSTION ENGINE.

1,198,654.

Specification of Letters Patent. Patented Sept. 19, 1916.

Application filed August 12, 1915. Serial No. 45,117.

To all whom it may concern:

Be it known that we, WILLIAM H. PALMER and JAMES F. PALMER, citizens of the United States, and residing in the city of Pittsburgh, in the county of Allegheny and State of Pennsylvania, have invented or discovered new and useful Improvements in Internal-Combustion Engines, of which the following is a specification.

10 Our invention comprises certain new and useful improvements in internal combustion engines, relating particularly to the valve mechanism of the same.

The object in view is the provision of a more efficient mechanism which will insure positive, economical and substantially noiseless action, result in material reduction in the number of parts used thereby working a great economy in cost of manufacture and upkeep, may be readily taken apart and replaced when necessary, but will not require adjustment while being used. These objects are attained by the use of an improved rotary valve mechanism which controls the introduction of the fuel charges into the cylinders and the expulsion of the products of combustion from the same, these operations being properly timed to explode the charges in the various cylinders of the engine in the predetermined order.

Numerous novel features of structure and arrangement of parts will appear from the following description.

In the accompanying drawings, which are intended merely to illustrate a practical embodiment of the principles of our invention and not to limit the scope of the latter to the construction shown, Figure 1 is a cross section of one of the engine cylinders taken along the line I—I in Fig. 5, showing a cylinder, its ignition and valve mechanism and its piston having begun the suction stroke; Fig. 2 is a diagrammatic view showing a piston having begun its compression stroke; Fig. 3 is a similar view showing a piston having begun its explosion stroke; Fig. 4 is a similar view showing a piston having begun its scavenging stroke; Fig. 5 is a longitudinal vertical section of a four cylinder engine embodying our invention taken along the line V—V in Fig. 1;

Fig. 6 is a horizontal section of the same taken along the line VI—VI in Fig. 1; Fig. 7 is a perspective of the valve body dismounted; Fig. 8 is a broken perspective of the valve bushing dismounted, and Fig. 9 is a diagrammatic front elevation showing a "twin cylinder" type of engine fitted with our invention.

Referring first to the longitudinal cylinder type of engine illustrated in Figs. 1 to 8, inclusive, the four cylinders are represented by A¹, A², A³, and A⁴, provided with pistons B¹, B², B³, and B⁴. The cylinders are shown fired in the usual order in a four cylinder engine, viz., A¹, A³, A⁴, and A², but it will be understood that any order of firing may be adopted as desired. For the sake of illustration we have shown the cylinders cast *en bloc* but the same may be cast in pairs or individually and suitably connected together, as may be found desirable.

1 is the ignition means or spark plug.

Through the head of the cylinder casting or castings a cylindrical bore C is provided which acts as a horizontal rotary valve seat, which bore is connected with the compression chamber of each cylinder by means of a cylinder port 2. One end of the valve seat C is closed, as shown in Figs. 5 and 6, while the other end of said seat is open.

D is the fuel manifold formed in the cylinder heads, parallel with and preferably on the same horizontal plane with the valve seat C. Said manifold is closed at both ends and provided with a central port 3 for connection with the carburetor or other source of fuel, not shown.

4 represents priming ports for provision of priming cocks.

In the same vertical plane with each of the cylinder ports 2 a fuel port 5 of the same horizontal width connects the manifold D with the valve seat C. Said fuel ports 5 expand vertically toward the manifold D to the vertical diameter of the latter, as shown in Fig. 1.

E is the exhaust manifold secured to the cylinders in the usual manner and connected to the valve seat C by means of ports 6 diametrically opposite to each port 5 and of equal dimensions at the valve seat. Said

ports 6 contract horizontally and expand vertically toward the manifold to a circular cross section, as shown in Fig. 1.

In the drawings, the ports 5 and 6 at 5 the valve seat are vertically 45 degrees of the circumference of the valve seat, $22\frac{1}{2}$ degrees on either side of the horizontal axis, while the cylinder ports are 60 degrees in extent, $22\frac{1}{2}$ degrees on the intake or fuel 10 side of the vertical axis and $37\frac{1}{2}$ degrees of the exhaust side of said axis. By thus off-centering the cylinder ports toward the exhaust ports, we are enabled to open communication between the cylinder port and 15 the exhaust port when the piston reaches a point at 30 degrees above the lowermost position of the crank, thus preventing jarring or hammering at the completion of the explosion stroke.

20 F is a cylindrical bushing, having its inner end closed, and snugly fitting in the valve seat C. To prevent rotation of said bushing in said seat, the former is provided with radial fins 7 which seat in recesses 8 25 in the wall of the valve seat. The wall of the bushing is provided with cutaway portions of equal size and registering with the ports in the valve seat, the bushing acting as a lining for the valve seat to take up wear 30 and to be removed and replaced when worn.

G is a solid rotary valve body of cylindrical cross section, fitting snugly in the bushing F and provided with a valve port 9 for each cylinder. The valve ports are 35 cut into the body of the valve body for an arc of 185 degrees. Said ports are cut in the vertical plane of the cylinder, fuel and exhaust ports of each cylinder, and in a four cylinder engine, the center line of one of 40 said valve ports is 90 degrees in advance, clockwise, of the center line of the valve port of the cylinder fired last preceding the cylinder of the first named valve port. Thus in Fig. 7 the center line of the first valve 45 port to the left is 90 degrees in advance of the center line of the second valve port, shown in dotted lines, said second valve port being 90 degrees in advance of the fourth valve port, while the fourth valve port is 90 50 degrees in advance of the third valve port, and the third valve port is 90 degrees in advance of the first valve port. In other words, the valve port of any given cylinder is 90 degrees in the rear of the valve port of 55 the cylinder fired next before the first named cylinder and 90 degrees in front of the valve port of the cylinder fired next behind the first named cylinder. Where the order of firing is different from that stated above, 60 the order or progression of the valve ports around the circumference of the valve body will be, of course changed from that shown. In the case of a six cylinder engine, the circumferential spacing of the valve ports

from center to center will be 60 degrees. 65 In a twelve cylinder engine said spacing will be 30 degrees from center to center.

The outer end of the valve body G protrudes from the valve seat and bushing and is of reduced diameter, as at 10, to extend 70 through the flanged bearing sleeve 11, attached to the engine, and its antifriction lining or bushing 12.

13 is a gear or sprocket chain casing extending up over said bearing, and 14 is a 75 gear or sprocket wheel keyed on the end 10 of the valve body within said casing and by means of which said valve body is rotated clockwise at half the speed of the crank shaft of the engine whereby said valve body 80 turns 90 degrees with each stroke of the pistons.

H represents the water jacket of the engine, cast integrally therewith or otherwise formed, surrounding the upper portions of 85 the cylinders and extending through the head of the engine about the valve seat and the fuel manifold, as shown. Above the valve bore the interior height, and consequently the capacity, of the water jacket enlarges toward the water outlet port 15.

16 is the water inlet port adjacent to the bottom of the water jacket to obtain a natural upward flow of the water as it becomes heated, the enlarging of the capacity of the 95 water jacket facilitating the escape of the heated water.

17 is a longitudinal web or partition dividing the water jacket above the valve bore into two compartments communicating together adjacent to the outlet 14, as shown in Fig. 5. Thus a better distribution of the cooling fluid in the head of the engine is obtained and the valve body and its seat are kept from overheating. The web also 105 strengthens the casting and reinforces the valve seat.

18 represents ports bored down through the web 17 at either side of each of the cylinders extending through the valve seat C 110 and the bushing F, the lower ends of said ports at the inner wall of said bushing being flared or beveled, as at 19, to facilitate the lateral distribution of lubricant between the bushing and the valve body. Oil or 115 grease cups, not shown, may be screwed into the upper ends of said ports 18. The right hand end port 18, beyond the web 17, may be carried through the water jacket by means of a tube 20.

21 is a horizontal passage bored through the cylinder casting beneath the web 17 and intersecting the ports 18. If cups are not to be mounted on the upper ends of the ports 18, the same may be plugged and a forced 125 oil feed connected to the passage 21, one end of said passage being open for such attachment, while its other end is closed.

When the passage 21 is not in use, its open end may be plugged.

Referring now to Figs. 1, 2, 3 and 4, wherein the four strokes of a piston of a four cycle engine are illustrated in their order, the operation of my invention, as illustrated, is as follows: At the beginning of the suction or intake stroke of the piston, the valve body is in position so that the forward edge of the valve port 9 is just passing the lower edge of the fuel port 5 and the piston's position is indicated by the dotted line *b* in Fig. 1. As the piston begins its downward travel, as shown in Fig. 1, the fuel port 5 is gradually exposed and the valve port 9 connects said fuel port with the cylinder port 2, so that fuel is sucked into the cylinder during the piston stroke. During the descent of the piston, the valve body *G* rotates 90 degrees, finally cutting off the cylinder port from the fuel port, and thus sealing the compression chamber of the cylinder. Fig. 2 shows the piston in the position occupied just after it has begun its next or compression stroke, during which the cylinder port 2 remains closed so that the charge previously sucked into the cylinder is compressed. As the piston begins its descent on the next or firing stroke, the ignition means 1 operates and the charge is fired, and as the valve body still closes the cylinder port, Fig. 3, the force of the explosion is exerted against the descending piston until the same is within 30 degrees of the lowermost position of the crank, when the valve body has turned sufficiently to cause the valve port 9 to connect the cylinder port 2 with the exhaust port 6, thereby relieving the explosion pressure in the cylinder and preventing jar-ring or hammering at the end of the stroke. As the piston rises on the scavenging stroke, Fig. 4, communication between the exhaust valve and the cylinder port is maintained, until the piston reaches substantially the top of its stroke, when the operation described in connection with Fig. 1 is repeated.

In Fig. 9 we have shown our invention applied to a multiple cylinder engine of the "twin" type, wherein the cylinders are arranged in pairs transversely aligned. The cylinders are represented by *A^a* and *A^b*, and their pistons by *B^a* and *B^b*, respectively. The valve seat *C¹*, with its bushing *F¹*, is located between the pair of cylinders. While the two cylinders are in the same vertical plane at right angles to the rotary valve and its seat, the respective cylinder ports, *2^a* and *2^b*, connect in tandem with the interior of the valve seat and its bushing, so that the valve ports are also in tandem on the valve body and spaced circumferentially to give the necessary progressive operation of the two cylinders dictated by the firing order adopted for the engine, as above de-

scribed. The position of the exhaust and fuel ports, *6^a* and *6^b*, and *5^a* and *5^b*, respectively, are the same relative to their respective cylinder ports, as described in the previous figures. The cylinder ports are shown carried into the valve seat from opposite sides, thereby shortening the length of said ports.

Where a single rotary valve mechanism, as shown in Fig. 9, is used for a twin cylinder engine, said valve mechanism may be placed in the location shown relative to the cylinders or the same may be placed at any angle or location relative to the cylinders by changing the angle of the cylinder ports connecting the cylinders with the valve body.

From the foregoing it is evident that a very substantial reduction in engine parts is effected by the use of our invention, and therefore the weight of the engine is greatly reduced and the cost of manufacture cut down materially. There are no parts to get out of adjustment and requiring constant attention, as where puppet valves are used, and the absence of chattering of the valve parts renders the operation of the engine relatively noiseless. The economy in weight and moving parts provides greater efficiency and the improved cooling and lubricating means provided prevents undue expansion or binding of the parts.

For the sake of illustration we have shown the valve body rotated clockwise, but it will be understood that said body may be revolved in either direction, and either in the direction of or contrary to the direction of rotation of the crank shaft of the engine. Where the valve body is to be rotated counterclockwise, the fuel ports would occupy the position of exhaust ports, and vice versa.

What we desire to claim is—

1. A valve for an internal combustion engine comprising a valve seat having a plurality of ports, a tubular bushing provided with a plurality of ports said bushing adapted to be inserted into the seat, coating means arranged within the seat and on the bushing to positively register the ports when the bushing is inserted into the seat, and a ported valve body arranged within said bushing adapted to control the various ports in the seat and bushing.

2. A valve for an internal combustion engine comprising a valve seat having a plurality of ports, a tubular bushing provided with a plurality of ports said bushing adapted to be inserted into the seat, grooves arranged within the seat and radial fins on the bushing adapted to positively register the ports when the latter is inserted into the seat, and a ported valve body arranged within said bushing adapted to control the various ports in the seat and bushing.

3. A valve for an internal combustion engine comprising a valve seat having a plurality of ports, a tubular bushing provided with a plurality of ports said bushing adapted to be inserted into the seat, grooves arranged within the seat and radial fins on the bushing, said grooves and fins respectively spaced at varying distances from each other so as to positively register the ports

in the seat and bushing when the latter is inserted into the seat, and a ported rotary valve body arranged within said bushing adapted to control the various ports in the seat and bushing.

Signed at Pittsburgh, Penna., this 11th 15 day of August, 1915.

WILLIAM H. PALMER.
JAMES F. PALMER.
